MASSAGING MACHINE

John A. Weaver, Greeley, Colo.

Application December 16, 1932
Serial No. 647,541

3 Claims. (Cl. 128—33)

This invention relates to improvements in massaging machines or devices and has reference more particularly to a device by means of which a person can massage his own back.

5 It is the object of this invention to produce a massaging machine or device in the form of a chair which shall be so constructed that a person seated on the chair can operate a movable massaging mechanism comprising massaging rollers 10 and move them up and down in contact with his own back.

The invention, briefly described, consists of a chair of solid and substantial construction which is provided with a straight back whose 15 height is substantially equal to the height of an ordinary person sitting on the chair. Secured to the chair and forming part of the back structure are two spaced parallel, vertical guides to which is slidably secured a frame having a shaft 20 on which is mounted for rotation a massage roller. Means comprising cords and pulleys are connected with the frame in such a way that the person sitting on the chair by exerting a pull on the ends of the cords can raise the massaging 25 mechanism which will travel along the guides. The parts are so adjusted that the roller will come in contact with the back of the person sitting on the chair and exert the desired massaging action.

30 For the purpose of moving the massaging mechanism downwardly, one or more weights are attached to it of sufficient value to overcome the resistance and to cause it to move downwardly when the tension is removed from the cords. A 35 head rest is also slidably secured to the guides in such a way that it can be adjusted to the proper height to suit the person operating the device. An elastic fabric is secured to the chair and provided with straps or buckles so arranged that the 40 operator can attach himself to the chair by means of the elastic fabric and in this way the operator will be held in proper position without undue effort.

Having thus briefly described the invention, the 45 same will now be described in detail, and for this purpose reference will be had to the accompanying drawing in which the preferred embodiment of the invention has been illustrated, and in which:

50 Fig. 1 is a side elevation of the massaging device showing a person in place thereon;
Fig. 2 is a rear view of the massaging device showing the same in inoperative position;
Fig. 3 is a section taken on line 3—3, Fig. 2;
55 Fig. 4 is a section taken on line 4—4, Fig. 2, and shows one form of head rest;

Fig. 5 is a view partly in elevation and partly in section showing the massaging mechanism that is slidably connected with the guides;

Fig. 6 is an end view of a massaging roller;

Fig. 7 is an edge view of the roller shown in Fig. 6; and

Fig. 8 is a section through the massaging roller.

In the drawing reference numeral 1 indicates the seat of a chair and this seat is supported on a frame 2 which in turn is supported on two short legs 3 and two upwardly extending legs 4. The exact construction of the frame work of the chair is immaterial as the invention is entirely independent of the specific construction except to the extent that the legs 4 extend upwardly to a greater height than the corresponding members of an ordinary chair. The rear legs 4 are connected at their upper ends by means of a transverse bar 5 and at a point below the seat by a transverse bar 6. Secured at their ends to the bars 5 and 6 are two guides 7. These guides may be round steel bars and are each provided at each end with a bracket 8 which is secured to the transverse bars by means of screws as shown. The back 70 of the chair may have spaced supporting portions 9 that are made out of ply wood or similar material and the adjacent edges of these members are spaced so as to provide an opening extending between the seat and the under side of the transverse bar 5. A head rest comprising a transverse bar 10 is slidably secured to the guides 7 and is provided with clamping screws 11 by means of which it can be held in adjusted position. On the front side of the bar 10 is a U-shaped bracket 12 whose ends are provided with pads 13 that can be adjusted to fit against the back of the neck of the operator in the manner shown clearly in Fig. 1.

90 Slidably connected with the guide 7 is a massaging device. This device consists of two metal castings which have been designated by reference numeral 14 and which may be substantially identical in size and shape. Each of the members 14 are provided with two lugs 15 that are perforated for the reception of the guide 7 in the manner shown quite clearly in Fig. 5. Each member 14 is also provided with a hub 16 which is perforated for the reception of one end of the shaft 17. The hub on the righthand member shown in Fig. 5 differs from that of the other member, in this, that it is provided with an opening 18 through one side. The reason for this opening is that whenever it is desired to substitute a new shaft and a new roller, this can readily be done by loosening the screw 19 of the clamping device 20, thereby making it possible to move the end of the 95 100 105 110

shaft 17 upwardly through the opening 18, whereupon it can be rotated about the lefthand guide 7 and extracted from the socket in the hub 16. After a new shaft has been inserted in the socket, 5 the parts are moved back into position and the shaft is moved downwardly through the opening 18 and clamped in position in the manner shown quite clearly in Fig. 5. The lugs or ears 15 are preferably spaced as far apart as practical so as 10 to prevent binding if the force applied to members 14 should vary in intensity. Secured to each member 14 is one end of a cord or cable 21 and these cords extend upwardly and over swivelled pulleys 22. The free ends of the cords are provided with hand grips 23 that can be grasped by the operator who is thus in position by merely moving his arms to raise and lower the massaging device. The guides 7 are so positioned with respect to the chair and the roller 24 is of such 15 size that when a person is properly adjusted, the roller will press against the back with the required amount of force. The guide 7 serves to predetermine the path of the roller and the operator by properly positioning his body can direct 20 the massaging action so that it will follow the line of his back bone in a manner quite obvious from the drawing. Each of the members 14 are provided with downwardly extending rods 25 to 25 which weights 26 are secured. The number of weights necessary to cause the massaging device to return is applied to the supporting bars 25, and therefore whenever the operator extends his arms in such a way as to draw the cords 21 upwardly, the massaging device will travel upwardly and 30 whenever the operator releases his tension on the cords, the massaging device will move downwardly by the action of gravity.

In order to properly position the operator an elastic fabric 27 is attached at one end to one of 40 the uprights 4 and is provided at its other end with buckles 27. Straps 28 are secured to the other upright and cooperate with the buckles as shown in Fig. 1. Since the fabric is elastic it permits a slight movement of the body, but 45 always exerts a constant yielding force tending to maintain the back against the uprights 9.

In the drawing only one form of massaging roller has been shown, but it is the intention to supply a number of different types of rollers and 50 rollers of different sizes so that any effect desired can be obtained. The massaging device itself is constructed in accordance with the disclosure in United States Patent No. 1,533,528, granted to me on April 14, 1925.

55 From the above description it will be apparent that by means of the massaging machine described, it is possible for any one to massage his own back to any extent desired and since such massaging action has been found by experience 60 to be a great benefit to the circulation and to the nervous system, the constant use of this device will soon give beneficial results.

In the form illustrated on the drawing and 65 description above, the invention has been shown as embodied in a structure of a specific construction, but it is obvious that the exact construction of the machine can be varied within reasonable limits and that the essential features consist 70 in the chair having a seat that supports the body

and having a back against which the back of the operator can rest and this chair back is provided with an opening extending from the seat to the head rest so as to permit the rollers to come in contact with the body. Any chair having the features just mentioned can be combined with the other features shown to produce the desired result.

Having described the invention what is claimed as new is:

1. A massage machine comprising, in combination, a chair having a seat and a back rest provided with an opening extending upwardly from the seat portion, guide bars located on opposite sides of the opening in the back rest, a massaging device slidably connected with the guide bars, said device comprising a roller which extends through the opening for engagement with the body of a person seated on the chair, a head rest adjustably secured to the guide bars, and means for reciprocating the massaging device along the guide bars, the last named means comprising cords attached at one end to the massage device and passing over pulleys attached to the back rest.

2. A massage machine comprising, in combination, a chair having a seat and a back rest provided with an opening extending upwardly from the seat, guide bars secured to the rear of the back rest on opposite sides of the opening, a head rest adjustably connected with the guide bars, a massage device slidably connected with the guide bars, said device comprising two members each slidably connected with a guide bar, a shaft connecting the two members, a roller mounted for rotation on the shaft, the roller being of such size that its forward side projects through the opening in the back rest and into position to engage the body of a person seated on the chair, pulleys secured to the back rest and cords attached to the massaging device and passed over the pulleys for moving the massaging device upwardly and means for returning the massage device when the tension is removed from the cords.

3. A massage machine comprising, in combination, a chair having a seat and a back rest provided with an opening extending upwardly from the seat, guide bars secured to the rear of the back rest on opposite sides of the opening, a head rest adjustably connected with the guide bars, a massage device slidably connected with the guide bars, said device comprising two members, each slidably connected with a guide bar, a shaft connecting the two members, a roller mounted for rotation on the shaft, the roller being of such size that its forward side projects through the opening in the back rest and into position to engage the body of a person seated on the chair, pulleys secured to the back rest and cords attached to the massaging device and passed over the pulleys for moving the massaging device upwardly, means for returning the massage device when the tension is removed from the cords, an elastic fabric secured to one side of the back rest, and means for releasably attaching it to the other side of the back rest.
